(57) **CLAIM**

I claim the ornamental design for a belt squat platform, as shown and described.

DESCRIPTION

FIG. 1 is a rear elevational view of the belt squat platform showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a front perspective view thereof; and,

FIG. 7 is a rear perspective view thereof.

The user stands on the platform with a specially designed belt around their waist. There is a chain that hangs from the belt, down through the deck of the platform, connected to a specially designed loading pin, that holds the weights.
